UNITED STATES PATENT OFFICE.

FREDERICK H. WILLCOX AND JOHN C. HAYES, JR., OF CHICAGO, ILLINOIS, ASSIGNEES
TO FREYN ENGINEERING COMPANY, OF CHICAGO, ILLINOIS, A CORPORATION OF
MAINE.

HEAT INTERCHANGER.

Application filed April 11, 1927. Serial No. 182,760.

The present invention relates to heat interchangers.

An object of the present invention is to provide a heat interchanger adapted for use with blast furnaces in which the hot gases emitted from a blast furnace are employed to heat the gas or air supplied to a blast furnace, which heat interchanger is efficient in operation and which may be readily cleaned.

10 A further object is to provide a heat interchanger which is very well adapted to meet the needs of commercial operation.

Further objects will appear as the description proceeds.

15 Figure 1 of the drawing illustrates a system embodying the principles of the present invention; and

Figure 2 shows a detail of construction.

The numeral 1 indicates a heat interchanger 20 to which communication is had through the conduit 2 adapted to conduct hot waste gas from hot blast stoves or other hot gas emitting devices. The hot gas from the conduit 2, after passing through the heat interchanger,

25 emerges through the conduit 3 into the stack 4. A damper 5 is provided for controlling the flow of gases through said conduit 3. Leading to the heat interchanger 1 is the pipe 6 adapted to conduct relatively cold gas from 30 a gas washer, and the numeral 7 indicates a pipe for conducting dry hot gas to burners, which may be the burners of hot blast stoves.

The heat interchanger 1, as shown in the drawing, comprises an elongated chamber 35 having the upper wall 9 and the lower wall 10. The two side walls of the heat interchanger provide the side walls of said chamber 8. Said chamber 8 communicates with the inlet conduit 2 and with the outlet conduit 3. Se-

40 cured in the top and bottom walls 9 and 10 of the chamber 8 are a plurality of spaced, vertically disposed flues 11-11, which open into the space 12 above the wall 9 and into the space 13 below the bottom wall 10. As will be

45 noted from the drawing, the inlet pipe 6 for cold gas has communication with one end of the heat interchanger 1, whereas the exit pipe from the dry hot gas leads from the opposite end of said heat interchanger 1. The pas-

50 sageway 13 has a decreasing cross sectional area from the inlet end thereof to the exit end thereof, while the passageway 12 has an increasing cross sectional area from the inlet end thereof to the outlet end thereof. It will

55 be clear without detailed explanation that

hot flue gases passing through the chamber 8 in proximity to the tubes 11-11 will communicate heat to the washed gas passing upwardly through the interior of said flues 11-11, conditioning said washed gas for delivery to burners.

Positioned above each of the flues 11-11 is a jet 14 for delivering a cleansing medium to the inner walls of said flues. Said jets are supplied from the pipes 15, which also 60 serve to support said jets. Said pipes 15 extend through the side wall of the heat interchanger and are connected to the water supply line 16. Connected to the water supply line 16 is the steam supply line 17. Said water supply line 16 and steam supply line 17 are 70 also connected to the upper portion of the passageway 13 at the bottom of the heat interchanger, whereby the heat interchanger may be completely flushed. The lower extremity 75 of the passageway or chamber 13 is provided with the hopper 18, which is provided with the pipe 19 controlled by the valve 20.

Each of the pipes 15 may be provided with a valve 21, whereby the flues associated with 80 each particular pipe may be flushed without interfering with the operation of the other flues. By reason of this construction a predetermined relatively small number of the total number of flues may be flushed without 85 taking the heat interchanger out of service. It will be understood, of course, that the number of jets responsive to any one valve may be chosen as desired.

The present invention contemplates a relatively great number of small diameter tubes. By reason of the vertical arrangement of the tubes and by reason of the convenient means for flushing said tubes, a small diameter of the tube is rendered possible, whereby the area 90 of heat transfer surface may be increased over prior practice in an installation occupying a predetermined space. By reason of the construction illustrated, the settling chamber or passageway 13 is provided for the reception of sludge below the bottom wall or tube sheet 10. By reason of the slanting position of the bottom wall of the chamber or passageway 13, the flushing water will interfere very little with the tubes which are not being 95 flushed, the water, after having flushed out any tubes, being out of the path of the incoming gas. As will be noted from the drawing, the inlet pipe 6 is located at a point materially above the hopper 18, the advantage 100 105 110

being that incoming gases through the pipe 6 will be out of the path of sludge or water collected in and above said hopper 18. By reason of the tapering arrangement of the passageways or chambers 12 and 13, the result is achieved that a substantially uniform flow of gas is had through each of the tubes or flues 11-11.

It will be understood, of course, that though the invention is particularly adaptable to blast furnace practice, and though the pipes 6 and 7 and flues 11-11 have been described as conveying gas, the invention is applicable to other arts, and any other medium may be used instead of gas.

Moreover, though water and steam have been referred to as the cleaning media, other media may be chosen if preferred.

Though a preferred embodiment has been described in detail, the disclosure should be considered in an illustrative way rather than in a limiting sense. Many modifications will occur to those skilled in the art. It is intended to cover all such modifications that fall within the scope of the appended claims.

What is claimed is:

1. A heat interchanger comprising a gas conducting chamber, flues vertically disposed within said chamber, a gas conduit communicating with said flues at the lower ends thereof and a gas conduit communicating with said flues at the upper ends thereof, said first mentioned conduit having an inlet at one end of said chamber and converging in cross sectional area toward the other end of said chamber, said second mentioned conduit having an outlet adjacent to the other end of said chamber and converging in cross sectional area from said other end toward said first mentioned end of said chamber, and flushing jets disposed within said second mentioned conduit and communicating with said flues for flushing said flues.
2. A heat interchanger comprising a gas conducting chamber, flues vertically disposed within said chamber, a gas conduit communicating with said flues at the lower ends thereof and a gas conduit communicating with said flues at the upper ends thereof, said first mentioned conduit having an inlet at one end of said chamber and converging in cross sectional area toward the other end of said chamber, said second mentioned conduit having an outlet adjacent to the other end of said chamber and converging in cross sectional area from said other end toward said first mentioned end of said chamber, and flushing jets disposed within said second mentioned conduit and communicating with said flues for flushing said flues, groups of said jets being controlled by individual valves whereby said groups may be flushed without interfering with the other of said flues.

3. A heat interchanger comprising a gas conducting chamber, flues vertically disposed within said chamber, a gas conduit communicating with said flues at the lower ends thereof and a gas conduit communicating with said flues at the upper ends thereof, said first mentioned conduit having an inlet at one end of said chamber and converging in cross sectional area toward the other end of said chamber, said second mentioned conduit having an outlet adjacent to the other end of said chamber and converging in cross sectional area from said other end toward said first mentioned end of said chamber, and flushing jets disposed within said second mentioned conduit and communicating with said flues for flushing said flues, the inlet to said first mentioned conduit being disposed materially above the outlet of said first mentioned conduit.

4. A heat interchanger comprising a gas conducting chamber, flues vertically disposed within said chamber, a gas conduit communicating with said flues at the lower ends thereof and a gas conduit communicating with said flues at the upper ends thereof, said first mentioned conduit having an inlet, said second mentioned conduit having an outlet and flushing jets disposed within said second mentioned conduit and communicating with said flues for flushing said flues.

5. A heat interchanger comprising a gas conducting chamber, flues vertically disposed within said chamber, a gas conduit communicating with said flues at the lower ends thereof and a gas conduit communicating with said flues at the upper ends thereof, said first mentioned conduit having an inlet, said second mentioned conduit having an outlet and flushing jets disposed within said second mentioned conduit and communicating with said flues for flushing said flues, groups of said jets being controlled by individual valves whereby said groups may be flushed without interfering with the other of said flues.

6. A heat interchanger comprising a gas conducting chamber, flues vertically disposed within said chamber, a gas conduit communicating with said flues at the lower ends thereof and a gas conduit communicating with said flues at the upper ends thereof, said first mentioned conduit having an inlet, said second mentioned conduit having an outlet, and flushing jets disposed within said second mentioned conduit and communicating with said flues for flushing said flues, the inlet to said first mentioned conduit being disposed materially above the outlet of said first mentioned conduit.

Signed at Chicago, Illinois, this 5 day of April, 1927.
